UNITED STATES PATENT OFFICE.

JAMES A. GREEN, OF DOLGEVILLE, NEW YORK, ASSIGNOR TO DANIEL GREEN FELT SHOE COMPANY, OF BOSTON, MASSACHUSETTS, A CORPORATION OF MASSACHUSETTS.

METHOD OF MAKING FELT SHOES.

1,081,955.

Specification of Letters Patent. Patented Dec. 23, 1913.

Application filed June 8, 1912. Serial No. 702,389.

To all whom it may concern:

Be it known that I, JAMES A. GREEN, a citizen of the United States, and a resident of Dolgeville, in the county of Herkimer 5 and State of New York, have invented certain new and useful Improvements in Methods of Making Felt Shoes, of which the following is a specification.

My invention relates to improvements in 10 methods of manufacturing felt shoes in which the vamp and upper are composed of felt or other shrinkable material and the sole is composed of leather and in which there is also a padded insole such as is 15 shown and described in the William R. Green Patent No. 894,733 of July 28, 1908.

The object of my invention is, among 20 other things, to improve upon the methods of constructing such felt shoes by which 25 there may be eliminated the sewed ridge along the inner thread of the shoe and to avoid the use of hand sewing which is now required in uniting the inner felt sole to the upper in shoes or slippers made in accordance with the William R. Green Patent No. 894,733.

In the accompanying drawings, which 30 form a part hereof—Figure 1 is a perspective view of a felt shoe or slipper made according to my invention; Fig. 2 is a cross-sectional view taken on the line 2—2 of Fig. 1 looking in the direction of the arrow; Fig. 3 is a longitudinal sectional view of a portion of the shoe or slipper taken on the line 35 3—3 of Fig. 2 looking in the direction of the arrow; Fig. 4 is a top plan view or detail of the sole with the padding thereon; Fig. 5 is a cross-sectional view taken on the line 5—5 of Fig. 1 looking in the direction of the arrow; Fig. 6 is a view similar to Fig. 5, but 40 with the last inserted in the shoe.

Similar numerals refer to similar parts throughout the several figures.

Referring now to the details of the drawings, 45 10 is the upper composed of felt or other shrinkable material and cut so as to form the upper part of a shoe or slipper and stitched at the rear part thereof at 11, as shown in Fig. 1.

12 is a separate piece or welt sewed in at the heel and at the bottom of the stitching 50 11 so as to form a pocket for a heel-pad to be inserted therein when the shoe is formed and completed.

13 is the sole composed preferably of 55 leather and cut to the shape and size required by the length and width of the felt shoe or slipper proper.

15 designates the line of stitching in securing the welt 12 to the upper 10. 60

16 is the inner felt sole or "sock lining" which forms the inner tread of the shoe and is stitched to the lower edge of the upper and upper edge of the welt 12 throughout its entire extent. 65

17 is the heel-pad which forms what is known as a spring heel, this heel-pad being cut to the size of the heel and inserted in the pocket formed by the spring welt 12 as shown in Figs. 2 and 3. 70

14^a is the stitching, preferably zig zag in formation, which unites the lower edge of the upper and the edge of the inner sole or sock lining. A second line of stitching 14 75 unites the outer sole 13 to the upper and sock lining and to the welt along the heel, as shown in Figs. 1 and 2.

18 is a stiffening inner sole or holder composed of buckram or other similar material, upon which is secured a soft pad of carded 80 wool 19 which extends over the entire sole 13 except a suitable margin, as shown in Fig. 4, to allow the upper and spring welt to be sewed to the sole 13. This padding 19 forms a cushion insole for the felt shoe or 85 slipper and is covered throughout by the inner felt sole or sock lining 16 and lies below the spring heel pad 17 as shown in Fig. 3.

20 is the last with a hollow bottom, as shown in Fig. 6, extending throughout the 90 length of the last and forming a concave recess within which the padding 19 and the sock lining 16 may be forced upwardly when the shoe is dampened and wetted and placed upon the last so as to shrink to give it the 95 desired form and finish.

My improved method which is shown in Figs. 1 to 6 inclusive is practised as follows:—The upper 10 is stitched along the rear at 11 and then the inner felt sole 16 100 and the spring welt 12 are stitched to such upper along the lower edge of the upper and the upper edge of the welt 12 as shown in Figs. 2 and 3, this being done preferably by cross-stitching 15 and can be accomplished by machinery. The edge of the insole 16 is united to the lower edge of the upper 10 forward of the welt 12 by the 105

zig-zag stitching 14^a as shown in Fig. 1. I next take the stiffener of buckram 18 and stitch to it the carded wool padding 19 and then glue or cement the buckram stiffener 18 to the leather sole 13, as shown in Fig. 4. The two separate parts are now placed in union with each other so as to form the shoe and the heel pad 17 is inserted in the pocket formed for it by the 10 welt 12 and the whole is exteriorly stitched at 14 throughout the entire extent of the sole, thereby uniting the outer sole 13, with its carded wool padding attached, to the upper 10 and the spring welt 12 along their 15 lower edges. The shoe is now in the condition shown in Fig. 5. The upper is now thoroughly dampened or wetted by plunging the same in water and while still being wet a hollow bottom last 20 is inserted with 20 in the interior parts of the shoe which stretches somewhat the upper and forces the inner padding or cushion sole 19 with its 25 spring welt 12 upward into the concave recess of the last and allowed to dry. During the process of drying the felt upper shrinks to 30 such an extent as to give shape and contour to the upper of the shoe and to allow the inner tread of the sole to be rounded while the outer sole 13 or bottom of the 35 shoe is substantially flat. The last is now removed and it will be observed, as shown in Fig. 6, that no ridge or creasing exists along the inner tread of the shoe, which in other forms exists, and my improved 40 method therefore prolongs the life of the shoe because there is no seam to be worn and also adds greatly to the comfort of the wearer by avoiding any such protruding seam or ridge to press against the bottom of the foot.

It will be observed that the object of my

improved method is accomplished by forming the shoe or slipper right side out and that after being properly wet and drawn 45 over a hollow bottom last and allowed to dry the shoe assumes the exact contour of the last because of the shrinking of the fibers of the felt or other shrinkable material to the lines and contour of the last 50 thereby giving the shoe a perfect shape and at the same time compelling the inner felt sole or sock lining with its inner pad or cushion insole to project upwardly into the tread of the shoe without any ridge or seam 55 along the exterior line of the inner tread.

What I claim as new and desire to secure by Letters Patent is the following, viz:—

The method of making shoes composed of felt or other shrinkable material, which 60 consists in stitching to the lower edge of an upper about the heel portion thereof the heel edge of an insole and the upper edge of a welt, said welt extending about the heel portion of the shoe only to form a pocket for 65 a heel pad, then stitching together the lower edge of the upper and the edge of the insole forward of the heel portion of the shoe, then securing a padding on the inner side of an outer sole, then placing the outer sole in 70 proper position beneath the inner sole, then inserting a heel pad in said pocket, then attaching the edge of the outer sole to the lower edge of the welt and the edges of the inner sole and upper forward of the heel 75 portion of the shoe, and finally shrinking the shoe so formed upon a hollow bottomed last.

JAMES A. GREEN.
